(57) **CLAIM**

The ornamental design for a foldable child height recording panels, as shown and described.

DESCRIPTION

FIG. 1 is a front view of a foldable child height recording panels; the back view being a mirror image;
FIG. 2 is a right side view thereof, the left side view being a mirror image;
FIG. 3 is a lower edge view thereof;
FIG. 4 is a top edge view thereof;
FIG. 5 is an isometric view thereof;
FIG. 6 is an upper detail view of a panel edge from FIG. 5 thereof;
FIG. 7 is a lower detail view of a panel edge from FIG. 5 thereof;
FIG. 8 is an isometric view of the panels in a folded position thereof;
FIG. 9 is a detailed view from FIG. 8 thereof; and,
FIG. 10 is a front view thereof with a child and measuring lines drawn in broken lines showing the foldable child height recording panels in a condition of use.
The features drawn in broken lines in FIGS. 1-5, 7, 8, 9, and 10 are an unclaimed hanging ring and unclaimed connecting string. Dash dash dot lines shown in FIG. 10 are unclaimed height markings. Other broken lines shown in FIG. 10 are for purposes of illustrating environmental structure associated with the claimed design in condition of use, and which forms no part of the claimed design.
